RAILWAY SWITCH OPERATING APPARATUS

Herbert L. Bone, Pittsburgh, Pa., assignor to The Union Switch & Signal Company, Swissvale, Pa., a corporation of Pennsylvania

Application November 1, 1933, Serial No. 696,206

14 Claims. (Cl. 246—291)

My invention relates to railway switch operating apparatus, and particularly to apparatus for operating railway switches which are intended to be trailed at times.

5 One object of my invention is to provide apparatus of the type described wherein a standard switch operating and locking device is controlled jointly by manually operable means and by means connected with the switch points in such manner 10 that the device is normally biased to a selected extreme position in which the switch points are locked in a corresponding extreme position, but that, when a train trails the switch, the device is then mechanically operated by the train to a 15 position to unlock and reverse the switch points, before sufficient force is exerted on the points to damage the points or the switch operating device, and is subsequently held in such latter position until after the train is completely past the switch, at which time the switch operating 20 device is restored to its original position by the biasing means.

I will describe two forms of apparatus embodying my invention, and will then point out the 25 novel features thereof in claims.

In the accompanying drawings, Fig. 1 is a top plan view showing one form of apparatus embodying my invention. Fig. 2 is an enlarged side view, partly sectioned, of the switch operating 30 mechanism B shown in Fig. 1. Fig. 3 is an enlarged vertical sectional view of the combined biasing and buffering device D shown in Fig. 1. Fig. 4 is a fragmentary sectional view of the device D shown in Fig. 3 taken on a plane parallel to, 35 and spaced from, the plane of Fig. 3. Fig. 5 is a top plan view showing a modified form of the apparatus illustrated in Fig. 1 and also embodying my invention. Fig. 6 is an enlarged vertical sectional view of the device D forming part of the 40 apparatus illustrated in Fig. 5.

Similar reference characters refer to similar parts in each of the several views.

Referring first to Fig. 1, the reference character A designates a railway switch comprising, as usual, two fixed rails 1 and 1^a and two movable rails 2 and 2^a. The fixed rails 1 and 1^a are laid on tie plates 3 and are secured to crossties 4 in the usual manner. The movable rails 2 and 2^a are fastened together by a front rod 5, a head rod 6, a bridle rod 7, and a tie rod 8, and may be moved into a normal or a reverse position by means of a switch operating mechanism B which is connected with the head rod 6 in a manner which I will describe hereinafter. When the 50 switch occupies its normal position in which posi-

tion it is shown in Fig. 1, the movable rail 2 engages the fixed rail 1, and the movable rail 2^a is spaced a slight distance from the fixed rail 1^a. When the switch is reversed, however, the movable rail 2^a then engages the fixed rail 1^a, and the movable rail 2 is spaced from the fixed rail 1.

The switch operating mechanism B is secured to one end of a tie strap 9 which is bolted to the ties 4 adjacent the outer side of the rail 1, and as here shown, comprises a base plate 10 upon which a motion plate 11 is guided to move longitudinally by means of rollers 12 journaled on studs 13 which project upwardly from the base plate. The motion plate is adapted to be reciprocated between two extreme positions in a manner which I will describe hereinafter, and has formed therein a cam slot 14 having a portion at each end which is parallel to the direction of movement of the motion plate and an intermediate connecting portion which is disposed at an angle 15 to the direction of movement of the motion plate. Extending into the cam slot 14 and cooperating therewith is a roller 15 mounted on a pin 16 secured to a throw bar 17. The throw bar 17 extends transversely of the motion plate, and is 20 guided to move longitudinally by means of the same rollers 12 which guide the motion plate 11. One end of the throw bar 17 is operatively connected with the previously described head rod 6 of the switch A.

The switch operating mechanism B also comprises a locking device 18 (see Fig. 2) which is secured to the left-hand end of the motion plate, and which in the form here shown comprises an upper bar 18^a and a lower bar 18^b riveted together in parallel spaced relation. Attached to the bars 18^a and 18^b, respectively, is a normal locking dog 19^a and a reverse locking dog 19^b, which locking dogs cooperate respectively with normal notches 20^a and reverse notches 20^b formed in the upper and lower edges of an adjustable lock rod L. The lock rod L is of the usual and well-known construction, and is connected to the front rod 5 of the switch A in the usual manner.

The portion of the apparatus thus far described is well known and its operation is well understood, so that for purposes of the present disclosure the following brief description of the operation of this portion of the apparatus is believed to be sufficient. When the motion plate 11 occupies its extreme left-hand or normal position in which position it is shown in the drawings, the movable rails of the switch A are securely held in their normal positions by engagement of the roller 15 with the right-hand end of the

cam slot 14, and under these conditions, the normal locking dog 19^a enters the normal notches 20^a in the lock rod L and locks the movable rails in their normal positions. When, however, 5 the motion plate is moved from its extreme normal position to its opposite extreme or reverse position, the first part of the movement of the motion plate withdraws the normal locking dog 19^a from the normal notches 20^a in the lock rod 10 L, the intermediate part of the movement of the motion plate causes the switch points to be moved to their reverse extreme positions, and the final part of the movement of the motion plate moves the reverse locking dog 19^b into engagement 15 with the reverse notches 20^b in the lock rod L to lock the movable rails in their reverse positions. The operation of the apparatus when the motion plate is subsequently restored to its extreme normal position is exactly the reverse 20 of that just described, and will be obvious from an inspection of the drawings.

The motion plate 11 is operatively connected by means of a turnbuckle 21 and a link 22 with the long arm 23^a of a bell crank lever 23. The bell crank lever 23 is pivotally supported in a crank stand 24, and has its short arm 23^b pivotally connected with the piston rod 28 of a combined biasing and buffering device D. The short arm 23^b of the bell crank lever is also operatively connected with one end of an operating rod 25, the other end of which is operatively connected, by means of nuts 25^a and 25^b and a standard switch basket 27, with the previously referred to tie rod 9. A certain amount of clearance is provided between the nuts 25^a and 25^b and the switch basket 27 for reasons which will be made clear herein-after.

The tie rod 8 may be located at any suitable location, but will preferably be located approximately halfway between the heel and the point of the switch. The base 24^a of the crank stand 24 is secured to a base plate 26 which base plate, in turn, is secured to the previously described tie strap 9. It will be apparent, therefore, that any 45 loss of adjustment between the parts due to creepage of the ties is prevented.

The combined biasing and buffering device D may be of any suitable type but in the form illustrated in Figs. 3 and 4, this device comprises a suitable casing 29 provided in the lower part thereof with two axially aligned cylinders 30^a and 30^b. These cylinders are closed at their outer ends by cylinder heads 31^a and 31^b, and communicate at their inner ends with an axially aligned cylindrical chamber 32 having a somewhat larger diameter than the cylinders 30^a and 30^b. The piston rod 28 extends into the cylinders 30^a and 30^b through a stuffing box 33 and through a suitable opening 34 in the cylinder head 31^a, and has attached thereto two pistons 35^a and 35^b which are adapted to reciprocate in the two cylinders 30^a and 30^b, respectively. The pistons 35^a and 35^b are attached to the piston rod 28 in such positions that when the piston 35^a is in the center of the cylinder 30^a, the piston 35^b will be in the center of the cylinder 30^b. The cylinders 30^a and 30^b and the chamber 32 are intended to be filled with a suitable fluid, such as oil, and the stuffing box 33 forms a fluid type joint through which the piston rod may slide.

Surrounding the piston rod 28 between the two pistons 35^a and 35^b is a compressed coil spring 37. One end of this spring abuts against an inwardly extending annular flange 38^a forming part of a spring socket 39^a which is slid-

ably mounted in the inner end of the cylinder 30^a, and the other end of this spring abuts against an inwardly extending annular flange 38^b forming part of a spring socket 39^b which is slidably mounted in the inner end of the cylinder 30^b. The end of the spring socket 39^a opposite to the inwardly extending annular flange 38^a is provided with an outwardly extending annular flange 40^a which cooperates with a shoulder 41^a formed at the junction of the cylinder 30^a and the chamber 32, and the end of the spring socket 39^b opposite to the inwardly extending annular flange 38^b is likewise provided with an outwardly extending annular flange 40^b which cooperates with a shoulder 41^b formed at the junction of the cylinder 30^b and the chamber 32. A certain amount of clearance is provided between the flanges 38^a and 38^b and the piston rod 28 and also between the flanges 40^a and 40^b and the chamber 32, and the parts are so proportioned that when the pistons 35^a and 35^b are in the centers of the associated cylinders 30^a and 30^b if the flanges 41^a and 41^b are then engaging the shoulders 40^a and 40^b, respectively, the flanges 38^a and 38^b will be engaging the adjacent pistons 35^a and 35^b. It will be apparent, therefore, that the spring 37 constantly biases the piston rod 28 to its mid stroke position in which the pistons 35^a and 35^b are in the centers of the associated cylinders. 30

The cylinder wall of the cylinder 30^a is provided at its right-hand end with a leak groove 36^a, and the cylinder wall of the cylinder 30^b is similarly provided at its left-hand end with a leak groove 36^b. The function of these leak 35 grooves is to permit fluid to flow past the pistons under certain conditions which will be made clear hereinafter.

The upper part of the casing 29 has formed therein a reservoir 42 which is also intended to be filled with fluid. The cylindrical chamber 32 is constantly connected at or near its center with this reservoir by means of an opening 43 formed in the upper part of the chamber wall. As best seen in Fig. 3, the left-hand end of the cylinder 45 30^b is also connected with the reservoir 42 through a port 44, a regulating valve 45, and two ports 46 and 47. The regulating valve 45 may have any suitable form, but in the form here shown, this valve is similar in all respects to 50 that described in Letters Patent of the United States No. 1,869,604, granted Aug. 2, 1932, to William C. McWhirter, for Buffering devices for railway switches and the like. It is believed, therefore, that for purposes of the present disclosure, it is sufficient to state that the regulating valve 45 comprises a rotatable valve member 45^a provided with a plurality of restricted orifices 45^b, one or more of which may be brought into 55 registration with the port 46 by turning the valve member 45^a to the proper position.

The left-hand end of the cylinder 30^b is further connected with the reservoir 42 through two coaxial ports 50 and 51, as shown in Fig. 4. The flow of fluid through these ports is controlled by a poppet valve 52 comprising a valve member 52, carried by a valve stem 53, and cooperating with a valve seat 54 formed in the end of the port 50. The right-hand end of the valve stem 53 is fluted and extends into the 65 ports 50 and 51, while the left-hand end of the valve stem 53 slides in a guide bearing 55 formed in a plug 56 screwed into a threaded opening in the cylinder head 31^b. A spring 57 having one 70 end located in an annular recess 58 formed in 75

the plug 57 to center the spring with respect to the valve, engages the valve member 52 and constantly urges the valve member towards the valve seat 54. This spring is made sufficiently light in weight and the parts are so proportioned that the valve member 52 will move away from the valve seat 54, and permit fluid to flow from the reservoir 42 into the left-hand end of the cylinder 30^b as soon as the pressure of the fluid in the reservoir 42 becomes greater than that in the cylinder 30^b.

The right-hand end of the cylinder 30^a is connected with the reservoir 42 through a port 60, a regulating valve 61, and two ports 62 and 63, and also through two coaxial ports 64 and 65. The regulating valve 61 is similar in all respects to the regulating valve 45, and comprises a rotatable valve member 61^a provided with a plurality of restricted orifices 61^b, one or more of which may be brought into registration with the port 62 by turning the valve member 61^a to the proper position.

The flow of fluid through the ports 64 and 65 is controlled by a poppet valve b. This poppet valve is similar to the poppet valve a, and comprises a valve member 66 carried by a valve stem 67 and cooperating with a valve seat 68 formed in the end of the port 62. The left-hand end of the valve stem 67 is fluted and extends into the ports 64 and 65, while the right-hand end of the valve stem 67 is mounted to slide in a guide bearing 69 formed in a plug 70. The plug 70 is provided with an annular recess 71 which receives one end of a coil spring 72. The other end of the coil spring 72 engages the valve member 66 and constantly urges this valve member toward the valve seat 68. The spring 72 is made sufficiently light in weight and the parts are so proportioned that the valve member 66 will unseat itself and permit fluid to flow from the reservoir 42 into the right-hand end of the cylinder 30^a as soon as the pressure of the fluid in the reservoir 42 becomes greater than that in the right-hand end of the cylinder 30^a.

To facilitate the insertion of fluid into the device D, a screw plug 43^a is provided in the upper part of the reservoir 42, as shown in Fig. 3.

The operation of the device D, as a whole, is as follows: As shown in Figs. 3 and 4, all parts are in their normal positions; that is to say, the valves a and b are both closed, and the piston rod 28 is held in its mid stroke position by reason of the abutment of the spring 37 at its opposite ends against the flanges 38^a and 38^b of the spring sockets 39^a and 39^b, the engagement of the flanges 38^a and 38^b with the adjacent pistons 35^a and 35^b, and the engagement of the flanges 40^a and 40^b with the shoulders 41^a and 41^b, respectively.

I will now assume that with the parts in their normal positions as just described, a force is exerted on the piston rod 28 which moves it from its mid stroke position in which it is shown in Figs. 3 and 4, toward the right, to the right-hand end of its stroke. This movement of piston rod 28 toward the right, of course, moves the pistons 35^a and 35^b toward the right a like amount, and the movement of piston 35^b toward the right, in turn, moves spring socket 39^b toward the right. During this movement of spring socket 39^b toward the right, spring socket 39^a is held in the position shown, due to the engagement of the flange 40^a with the shoulder 41^a, and as a result, spring 37 becomes compressed, and exerts an increased force on the piston rod 28, which force

constantly tends to return the piston rod to its mid stroke position. The movement of piston 35^b toward the right also causes fluid to flow from cylinder 39^b on the right-hand side of piston 35^b through leak groove 38^b into cylinder 30^b on the left-hand side of piston 35^b, until piston 35^b passes the right-hand end of leak groove 38^b, whereupon valve a opens and permits fluid to flow from cylinder 30^b on the right-hand side of piston 35^b through chamber 32, opening 43, reservoir 42, ports 59 and 51, and valve a into cylinder 30^a on the left-hand side of piston 35^a; while the movement of piston 35^a toward the right causes fluid to flow from cylinder 30^a on the right-hand side of piston 35^a through leak groove 36^a into cylinder 39^a on the left-hand side of piston 35^a. The leak grooves 36^a and 38^b are made relatively large so that fluid can flow through these grooves at a relatively rapid rate, and as was previously pointed out, the pressure exerted on the valve member 52 of valve a is comparatively small, so that very little pressure is required to open valve a. It will be apparent, therefore, that during movement of piston rod 28 from its mid stroke position to the right-hand end of its stroke, the fluid in the device D offers very little resistance to the movement of the piston rod, and that practically all the resistance which is offered to the movement of the piston rod under these conditions is that which is necessary to overcome friction and to compress the spring 37.

I will now assume that after piston rod 28 has been moved, in the manner just described, to the right-hand end of its stroke as viewed in Figs. 3 and 4, the force which moved it there is removed, so that the piston rod is free to return to its normal or mid stroke position under the action of the spring 37. Under these conditions, as soon as the piston rod starts to move, spring 57 closes valve a, thus preventing fluid from flowing past this valve, and as a result, the return movement of the piston rod is then limited to the rate at which the fluid in the cylinder 39^b on the left-hand side of piston 35^b can flow through the regulating valve 45, until piston 35^b has passed the right-hand end of leak groove 38^b, it being obvious, of course, that during the whole return movement of the piston rod, the fluid in cylinder 30^a on the left-hand side of piston 35^a is free to flow past piston 35^a through leak groove 36^a into cylinder 39^a on the right-hand side of piston 35^a. The rate at which fluid can flow through the regulating valve 45 may be varied in the manner previously described, and it will be apparent, therefore, that the rate at which the piston rod 28 can return to its mid stroke position under the conditions just described may be adjusted to any desired value.

If piston rod 28 is moved to the left-hand end of its stroke from its mid stroke position, spring socket 39^b will be held in the position shown, due to the engagement of flange 40^b with the shoulder 41^b, and spring socket 39^a will be moved toward the left by piston 35^a, thus compressing spring 37, and hence causing the spring to exert an increased force on the piston rod 28 tending to restore the piston rod to its mid stroke position. During the movement of the piston rod to the left, fluid in the left-hand side of cylinder 30^b flows through leak groove 38^b into cylinder 30^b on the right-hand side of piston 35^b, while fluid in the left-hand side of cylinder 30^a flows through leak groove 36^a into cylinder 30^a on the right-hand side of piston 35^a, until pis-

ton 35^a passes the left-hand end of leak groove 36^a, whereupon valve b opens and permits fluid to flow from cylinder 39^a on the left-hand side of piston 35^a through chamber 32, opening 43, reservoir 42, ports 64 and 65, and valve b into cylinder 38^b on the right-hand side of piston 35^a. It will be apparent, therefore, that during movement of the piston rod 23 to the left from its mid stroke position, the fluid in the device offers substantially no resistance to the movement of the piston rod, and that substantially all the resistance which is offered to the movement of the piston rod is that due to spring 37.

After piston rod 28 has been moved to the left-hand end of its stroke, if the force which moved it there is then removed, piston rod 28 will then return to its normal position under the action of spring 37 in substantially the same manner as when the piston rod is moved to the right-hand end of its stroke and the force which moved it there is removed. Under these latter conditions, however, the rate of movement will be controlled by the valve 61 in a manner which will be readily understood from the foregoing description without further detailed description.

The buffing device D is slidably supported between two plates 73 and 74 which are secured to an adjacent pair of the ties 4, and is operatively connected by means of a link 77 with a suitable manually operable switch-throwing device here shown, for purposes of illustration, as a hand lever 75 pivotally mounted in a plate 76 secured to the same pair of ties 4 to which the plates 73 and 74 are secured.

The operation of the apparatus, as a whole, is as follows: When the hand lever 75 is rotated to its normal position in which it is shown in the drawings, the device D is moved bodily away from the track to what I shall term its "normal" position, and the parts are so proportioned that under these conditions a force will be exerted on the motion plate 11 of mechanism B through the medium of spring socket 38^a, spring 37, spring socket 39^b, piston 35^b and piston rod 28 of device D, and the linkage which connects piston rod 28 with the motion plate, which force will be sufficient to move the motion plate to, and hold it in, its normal position, except under certain conditions presently to be described. When, however, the hand lever 75 is rotated from its normal position through an angle of substantially 180° to its reverse position, the device D is then moved bodily toward the track to what I shall term its "reverse" position, and the parts are so proportioned that under these latter conditions, a force will then be exerted on the motion plate through the medium of spring socket 39^b, spring 37, socket 38^a, piston 35^a and piston rod 28 of device D, and the linkage which connects piston rod 28 with the motion plate 11, which latter force will be sufficient to move the motion plate to, and hold it in, its reverse position, except under other conditions which will be described hereinafter. As was previously pointed out, when the motion plate 11 is moved to its normal position, the switch A is moved to, and locked in, its normal position, and when the motion plate is moved to its reverse position, the switch A is moved to, and locked in, its reverse position. It follows, therefore, that the switch A will normally be moved to, and locked in, its normal or its reverse position, according as the hand lever 75 is moved to its normal or its reverse position. The operating rod 25 is so adjusted that when the switch A and hand throw lever 75 are both in their

normal positions, the nut 25^a will tightly engage the switch basket 27 and will exert a force on the movable rails through the medium of the switch basket 27 and tie rod 8 which tends to hold the movable rails in their normal positions, but that, when the switch and hand throw lever 75 are both in their reverse positions, the nut 25^b will then tightly engage the switch basket 27 and will exert a force on the movable rails through the medium of the switch basket and the tie rod 8 which latter force tends to hold the movable rails in their reverse positions. The operating rod 25 is further so adjusted that when the switch is being moved from its normal position to its reverse position, the nut 25^b will not move into engagement with the switch basket until after the motion plate 11 has been moved away from its normal position far enough to unlock the switch, and that when the switch is being moved from its reverse to its normal position, the nut 25^a will not move into engagement with the switch basket until after the motion plate has been moved away from its reverse position far enough to unlock the switch. It will be apparent, therefore, that when the hand lever is moved to either extreme position, a force will be exerted on the movable rails at the point where the tie rod 8 connects these rails, which force will aid that due to the switch operating mechanism in moving the movable rails to the extreme position corresponding to the position to which the lever 75 is moved.

I will now assume that the parts are in their normal positions as shown in Fig. 1, and that a train trails the switch. Under these conditions, as the leading wheels of the train roll along the fixed rail 1 and the movable rail 2^a, a force is exerted on the movable rails which tends to move them to their reverse positions. This force is initially resisted at the points of the rails by the engagement of the roller 15 carried by the throw bar 17 of the switch operating mechanism B with the straight portion at the right-hand end of the cam slot 14 in the motion plate 11, and also by the engagement of the locking dog 19^a with the notches 20^a in the lock rod L, and since the rails are somewhat resilient, this force causes the rails to become bent in such a way that the tie rod 8 is moved downwardly as viewed in Fig. 1. It will be apparent that any downward movement of the tie rod 8 acts through the linkage which connects the tie rod 8 with the motion plate 11 of the mechanism B to move the motion plate from its normal position toward its reverse position an amount which depends upon the ratio of the short and long arms of the bell crank lever 23; and the parts are so proportioned that the downward movement of the tie rod 8, which occurs before the force exerted at the points of the movable rails tending to move them to their reverse positions has a magnitude which is anyways near the magnitude of the opposing force which the mechanism B is capable of exerting, will cause sufficient movement of the motion plate 11 to withdraw the locking dog 19^a from engagement with the notches 20^a in the lock rod L, and to move the roller 15 carried by the throw bar 17 out of the straight portion at the right-hand end of the cam slot 14, and into the inclined central portion of the cam slot. As soon as the locking dog 19^a is withdrawn from the notches 20^a in the lock rod and the roller 15 enters the inclined central portion of the cam slot, the movable rails are, of course, free to move to their reverse positions, and as the leading wheels of the train continue their movement toward the points of the movable

rails, the movable rails, at the positions at which they are connected by the tie rod 8, are forced to their full reverse positions. The resultant additional movement of the tie rod 8 causes the motion plate 11 of the mechanism B to move toward its reverse position far enough to move the roller 15 out of the inclined portion of the cam slot 14 of the motion plate and into the straight portion at the left-hand end of the cam slot, thus forcing the movable rails to their full reverse positions at the points of these rails by means of the mechanism B. The downward movement of the tie rod 8 caused by the trailing train, in addition to operating the mechanism B in the manner just described, also moves the piston rod 28 of the combined biasing and buffering device D downwardly, and since the casing of the device D is held stationary under these conditions due to its connection with the hand lever 15, the spring 37 of the device D becomes compressed and exerts a relatively large force which tends to restore the movable rails to their normal positions at the position at which they are connected by the tie rod 8, and also to restore the motion plate 11 to its normal position. As long, however, as the train continues to trail the switch, the movable rails are held in their full reverse positions because the buffering action of the device D limits the movement of the motion plate to a relatively small amount, and since the roller 15 is then in the straight portion at the left-hand end of the cam slot 14 in the motion plate, a limited amount of movement of the motion plate back and forth can occur without any motion of the movable rails. It will be apparent, therefore, that with apparatus embodying my invention, the greater part of the wear on the switch points which occurs during trailing with the conventional type of spring switch is entirely eliminated. After the train has trailed completely through the switch, the spring 37 of the device D (retarded, of course, by the buffering action of the device) forces operating rod 25 upwardly, and motion plate 11 toward its normal position. The initial part of the upward movement of the rod 25 causes a force to be exerted on the movable rails tending to move them toward their normal positions before motion plate 11 is moved far enough toward its normal position to move roller 15 out of the straight portion at the left-hand end of the cam slot and into the inclined central portion of the cam slot, and it will be apparent, therefore, that the movable rails must deflect slightly before the points of these rails are released by the motion plate. After the points of the movable rails have once been released, however, the motion of the motion plate moves the movable rails to their normal position. During the last part of the movement of the movable rails to their normal position, the nut 25^a moves away from the switch basket 27, this movement being made possible by the previously described clearance between the nuts 25^a and 25^b of the operating rod 25 and the switch basket 27. After the movable rails have reached their full reverse positions, however, the roller 15 then enters the straight portion at the right-hand end of the cam slot and the clearance between the nut 25^a and the switch basket is taken up and the locking dog 19^a is moved into the notches 20^a in the lock rod 20. When the motion plate has been returned to its full normal position, all parts are then restored to their normal positions in which they are shown in the drawings.

75 It should be pointed out that there is a difference in the relation of the parts of the apparatus when the switch is moved to its reverse position by means of the hand lever and when the switch is trailed to its reverse position, this difference being that when the switch is moved to its reverse position by means of the hand lever, nut 25^b of operating rod 25 is in engagement with switch basket 27, roller 15 is moved well into the straight portion at the left-hand end of the cam slot 14 in the motion plate 11 of the mechanism B, 10 and the reverse locking dog 19^b occupies the reverse notch 20^b in the lock rod L; whereas, when the switch is trailed to its reverse position, nut 25^a is in engagement with switch basket 27, roller 15 has just barely entered the straight portion at 15 the left-hand end of the cam slot 14 in the motion plate 11, and the reverse locking dog is not in engagement with the corresponding notch in the lock rod.

When the switch occupies its reverse position 20 and a train trails the switch, the operation of the apparatus is similar to that just described, except that the movement of the various parts is reversed in direction, and it is believed, therefore, that this operation will be readily understood 25 from an inspection of the drawings and from the foregoing description without further detailed description.

It is well-known that some switches are stiffer, and therefore more difficult to operate than others. The force which the spring 37 in the buffering device D can be made to exert is limited to the force which will not derail the lightest cars which are permitted to trail the switch, and when the apparatus embodying my invention is used in connection with a switch which is unusually difficult to operate, it may be necessary, in order to secure the proper operation of the switch, to decrease the ratio of the levers 23^a and 23^b of the bell crank lever 23 to the extent that when a train 40 trails the switch, the motion plate of the operating mechanism B will not be moved far enough to cause the roller to enter the straight portion at the end of the cam slot in the motion plate opposite to the end which it occupied before 45 the train started to trail the switch. With the parts constructed in this manner, the movable rails of the switch will not be positively held in the extreme position to which they are moved during the trailing, but since the effect of the spring which tends to restore the rails to their movable positions is applied at the mid points of the movable rails, rather than at the forward ends of these rails as is the case in conventional 50 spring switches, the pressure exerted at the points of the movable rails against car wheels during trailing, will be very much less than that which is exerted with the conventional type of spring switch, and the wear, therefore, on the movable rails will be much less. The reduction in pressure at the points of the movable rails is due first to the mechanics of the layout which, since the spring load which is the same as for conventional 55 spring switches, is at the mid point rather than at the tips of the movable rails, results in the reaction at the points of the rails being one-half of the spring load, and secondly, because the points of the movable rails are free and will, therefore, bend back and thus relieve the pressure. 60

One advantage of proportioning the parts in the manner just described over proportioning them in the manner first described is that the latter proportioning causes less travel of the motion plate, and since the ratio of the arms of the 75

bell crank lever 23 is decreased, the force which the motion plate will exert to move the points of the movable rails to their extreme positions will be correspondingly greater for any given strength of spring in the combined biasing and buffing device D.

Referring now to Fig. 5, in the modified form of the apparatus here shown, the combined biasing and buffing device D shown in Fig. 1 has been replaced by a combined biasing and buffing device D¹, and the hand throw lever 75 shown in Fig. 1 has been replaced by a hand throw lever 81. The device D¹ is similar in all respects to the device D with the exception that the device D¹ is provided, in place of the piston rod 28 of the device D with a piston rod 28^a which extends completely through the device (see Fig. 6), and rack teeth 83 have been formed on the casting of the device.

As shown in Fig. 5, one end of the piston rod 28^a of the device D¹ is operatively connected, by means of the turnbuckle 21, with the motion plate 11 of the mechanism B, and the other end of the piston rod 28^a is operatively connected, by means of a link 82, with the long arm 23^a of the bell crank lever 23. The buffing device D¹ is mounted for longitudinal sliding movement adjacent a suitable guide plate 84, and is operatively connected with the hand lever 81 through the medium of a gear wheel 85 which is secured to the hand lever and which meshes with the rack teeth 83. All parts of the apparatus shown in Fig. 5 which have not been specifically mentioned are similar in all respects to the corresponding parts of the apparatus shown in Fig. 1.

The operation of the apparatus shown in Fig. 5 is substantially the same as the operation of the apparatus shown in Fig. 1. When the hand throw lever 81 occupies its normal position in which it is shown in the drawings, the device D¹ is moved toward the left to what I shall term its "normal" extreme position, but when the hand throw lever is rotated from its normal position through an angle of substantially 180° in a clockwise direction to its reverse position, the device D is then moved toward the right to what I shall term its "reverse" position. The parts are so proportioned that when the device D occupies its normal extreme position, it will bias the motion plate 11 of the mechanism B to its normal position, but that, when the device occupies its reverse extreme position, it will then bias the motion plate 11 to its reverse position. It follows, therefore, that the switch A will normally be moved to and locked in its normal or its reverse position according as the hand lever 81 occupies its normal or reverse position, and that the switch may be moved from its normal to its reverse position, and vice versa, by rotating the hand lever 81 from its normal to its reverse position, and vice versa. The parts are further so proportioned that when the device D¹ occupies its normal position, the nut 25^a of the operating rod 25 will engage the switch basket 27, and will thus exert a force on the movable rails of the switch through the medium of the switch basket and the tie rod 8, which force will urge the movable rails to their normal positions, and that when the device D¹ occupies its reverse position, the nut 25^b of the operating rod 25 will then engage the switch basket 27 and will exert a force on the movable rails through the medium of the switch basket and tie rod 8, which latter force will urge the movable rails to their reverse positions; but that,

when the switch is moved from either extreme position to the other extreme position, the nut which is out of engagement with the switch basket at the beginning of the movement will not move into engagement with the switch basket until after the motion plate 11 has been moved away from its original position far enough to unlock the switch.

I will now assume that the parts are in their normal positions as shown in Fig. 5, and that a train trails the switch. Under these conditions, as the leading wheels of the train roll along the fixed rail 1 and movable rail 2^a the movable rails become bent and move the tie rod 8 downwardly in the manner previously described in connection with the apparatus shown in Fig. 1, thus causing the piston rod 28^a of the device D to move toward the right and the motion plate 11 of the mechanism B to simultaneously move toward its reverse position. The movement of the piston rod 28^a of the device D¹ toward the right compresses spring 31 of this device in a manner which will be understood from the foregoing and from an inspection of the drawings, thus causing the device to exert an increased force tending to restore the rails to their normal positions and the motion plate to its normal position; while the movement of the motion plate 11 of the mechanism B toward its reverse position unlocks the switch and causes roller 15 to move out of the straight portion at the right-hand end of the cam slot 14 in the motion plate 11 and into the inclined central portion of the slot. As soon as the movable rails of the switch become unlocked, these rails, at the point where they are connected by the tie rod 8, are forced to substantially their full reverse positions by the wheels of the train, and this additional movement causes further movement of piston rod 28^a toward the right and motion plate 11 toward its reverse position. The last mentioned movement of the piston rod 28 causes additional compression of the spring 31 of the device D¹, while the last mentioned movement of the motion plate causes the roller 15 of the mechanism B to move out of the inclined central portion of the cam slot 14 and into the straight portion at the left-hand end of the cam slot, thus forcing the points of the movable rails to their full reverse positions. After the points of the rails have been moved to their full reverse positions by the motion plate in the manner just described, the buffing action of the device D is effective to hold them there until the train has completely passed the switch. When this happens, the spring 31 of the device D slowly restores the piston rod 28^a of the device toward its original position, thus causing the motion plate 11 to move toward its normal position and the operating rod 25 to move upwardly. The force which is exerted on the operating rod before the motion plate has moved far enough to cause the roller 15 to move out of the straight portion at the left-hand end of the cam slot and into the inclined central portion, causes the rails to deflect a certain amount, but as soon as the roller moves into the inclined portion of the slot, the motion of the motion plate causes the rails to be moved to and locked in their normal positions. During a part of the movement of the rails to their normal positions by the motion plate, the nut 25^a moves away from the switch basket 27, but after the movement of the rails has been completed and the roller 15 of the mechanism has entered the straight por-

tion at the right-hand end of the cam slot 14, the nut 25 again moves into engagement with the switch basket 27, thus causing a force to be exerted on the rails at the point where they are connected by the tie rod 8 which force aids the mechanism B in holding the rails in their normal positions.

When the switch has been moved to its reverse position by means of the hand lever 81, and a train trails the switch, the operation of the apparatus is similar to that just described except that the direction of the movement of the parts is reversed, and it is believed therefore that this latter operation will be understood from an inspection of the drawings and from the foregoing description without further detailed description.

One advantage of apparatus embodying my invention over the types of apparatus heretofore employed for operating a spring switch is that since the actual motion of the switch points is effected by a switch operating and locking device, a mechanical structure is provided which is more reliable for holding the switch points closed under normal conditions than one which depends upon a spring for holding the points closed.

Another advantage of apparatus embodying my invention over the types of apparatus heretofore employed for operating a spring switch is that by designing the motion plate properly, a high mechanical advantage at the end of the switch stroke can be obtained, and thus the points of the movable rails can be forced closed under unfavorable circumstances where, with the conventional type of spring means for closing the points sufficient force would not be available.

Another advantage of apparatus embodying my invention over the types of apparatus heretofore employed for operating a spring switch is that the force exerted by the points of the movable rails against the car wheels during trailing is much less than with the prior types of spring switches, and the wear on the switch points is therefore considerably reduced, thus prolonging the life of the switch and decreasing the cost of maintenance.

Still another advantage of apparatus embodying my invention over the types of apparatus heretofore employed for operating a spring switch is that the movable rails of the switch are normally securely locked in both extreme positions and the switch can be trailed in either extreme position without damaging the switch.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a railway switch, a switch throwing and locking mechanism operatively connected with said switch, a combined biasing and buffing device operatively connected with said mechanism, means for moving said device in a manner to actuate said mechanism between its two extreme positions, and other means for actuating said mechanism controlled by a train approaching said switch in a trailing direction.

2. In combination, a railway switch; a switch throwing and locking mechanism movable between normal and reverse positions and opera-

tively connected with said switch in such manner that said switch will be moved to, and locked in, its normal or its reverse position according as said mechanism is moved to its normal or its reverse position, means including a spring for moving said mechanism between its two extreme positions, a tie rod connecting the movable rails of said switch at a point between the heel and the point of the switch, and means connected with said tie rod and responsive to the lateral bending of the rails which takes place when a train starts to trail the switch for actuating said mechanism to unlock the switch until after the train is completely past the switch.

3. In combination, a railway switch; a switch throwing and locking mechanism movable between normal and reverse positions and operatively connected with said switch in such manner that said switch will be moved to, and locked in, its normal or its reverse position according as said mechanism is moved to its normal or its reverse position, means including a spring for moving said mechanism between its two extreme positions, a tie rod connecting the movable rails of said switch at a point between the heel and the point of the switch, and means connected with said tie rod and responsive to the lateral bending of the rails which takes place when a train starts to trail the switch for actuating said mechanism to unlock the switch until after the train is completely past the switch.

4. In combination, a railway switch; a switch throwing and locking mechanism movable between normal and reverse positions and operatively connected with said switch in such manner that said switch will be moved to, and locked in, its normal or its reverse position according as said mechanism is moved to its normal or its reverse position, a device provided with a piston rod which is movable from a mid stroke position to either of two extreme positions in opposition to the bias of a spring and with means for retarding movement of said piston rod by said spring, manually operable means for moving said device between a normal and a reverse position, a bell crank lever having one arm operatively connected with said mechanism, means for operatively connecting the other arm of said bell crank lever with said piston rod in such manner that said mechanism will be biased to its normal or its reverse position according as said device is moved to its normal or its reverse position, and means mechanically actuated by a train trailing said switch for actuating said mechanism to a position in which said switch is unlocked until after the train is completely past the switch.

5. In combination, a railway switch; a switch throwing and locking mechanism movable between normal and reverse positions and operatively connected with said switch in such manner that said switch will be moved to, and locked in, its normal or its reverse position according as said mechanism is moved to its normal or its reverse position; a device provided with a piston rod which is movable from a mid stroke position to either of two extreme positions in opposition to the bias of a spring and with means for retarding movement of said piston rod by said spring, manually operable means for moving said device between a normal and a reverse position, a bell crank lever having one arm operatively connected with said mechanism, means for operatively connecting the other arm of said bell crank lever with said piston rod in such manner that said

- mechanism will be biased to its normal or its reverse position according as said device is moved to its normal or its reverse position, and means mechanically actuated by a train trailing said 5 switch for actuating said mechanism from the extreme position it occupies at the beginning of the trailing toward its other extreme position far enough to reverse the switch until after the train has completely passed the switch.
- 10 6. In combination, a railway switch; a switch throwing and locking mechanism movable between normal and reverse positions and operatively connected with said switch in such manner that said switch will be moved to, and locked in, its normal or its reverse position according as said mechanism is moved to its normal or its reverse position; a device provided with a piston rod which is movable from a mid stroke position to either of two extreme positions in opposition to the bias of a spring and with means for retarding movement of said piston rod by said spring, manually operable means for moving said device between a normal and a reverse position, a bell crank lever having one arm operatively connected 15 with said mechanism, means for operatively connecting the other arm of said bell crank lever with said piston rod in such manner that said mechanism will be biased to its normal or its reverse position according as said device is moved to its 20 normal or its reverse position, a tie rod connecting the movable rails of said switch at a point approximately midway between the heel and the point of the switch, and means for connecting said tie rod with said other arm of said bell crank lever in such manner that the movable rails of the switch at the point where they are connected with the tie rod will be biased to their normal or their reverse positions according as said device occupies its normal or its reverse position 25 and that when a train trails the switch said mechanism will be actuated through the medium of said bell crank lever and in opposition to the bias of said device to a position in which said switch is unlocked until after the train is completely past the switch.
- 30 7. In combination, a railway switch; a switch throwing and locking mechanism movable between normal and reverse positions and operatively connected with said switch for moving said switch to, and locking it in, its normal and reverse positions, a combined biasing and buffering device provided with a piston rod which is biased to a mid stroke position and is movable to two extreme positions and with means for retarding movement of said piston rod in response to its bias, means for moving said device bodily between a normal and a reverse position, means for operatively connecting the piston rod of said device with said switch throwing and locking mechanism in such manner that said mechanism will be biased to its normal or its reverse position according as said device is moved to its normal or its reverse position, and means mechanically actuated by a train approaching said switch in a trailing direction for operating said mechanism from the extreme position which it then occupies toward its opposite extreme position in opposition to the bias of said device far enough to unlock said switch until after the train is completely past the switch.
- 35 8. In combination, a railway switch, a member reciprocable between a normal and a reverse extreme position, means controlled by said member for moving said switch to its normal or its reverse position according as said member is moved to its normal or reverse position and for locking the switch in the extreme position to which it is moved by said member, a manually operable lever movable between two extreme positions, means including a combined biasing and buffering device for operatively connecting said lever with said member in such manner that said member will be biased to its normal or its reverse position by said device according as said lever is moved to its normal or its reverse position and that if said member is moved away from the position corresponding to the position of said lever said device will retard the return movement of said member to such corresponding position, and means actuated by a train approaching said switch in a trailing direction for actuating said member from the extreme position which it then occupies to its opposite extreme position until after the train has completely passed the switch.
- 40 9. In combination, a railway switch, a member reciprocable between a normal and a reverse extreme position, means controlled by said member for moving said switch to its normal or its reverse position according as said member is moved to its normal or its reverse position and for locking the switch in the extreme position to which it is moved by said member, a manually operable lever movable between two extreme positions, means including a combined biasing and buffering device for operatively connecting said lever with said member in such manner that said member will be biased to its normal or its reverse position by said device according as said lever is moved to its normal or its reverse position and that if said member is moved away from the position corresponding to the position of said lever said device will retard the return movement of said member to such corresponding position, and means actuated by a train approaching said switch in a trailing direction for actuating said member from the extreme position which it then occupies toward its opposite extreme position far enough to unlock said switch until after the train has completely trailed the switch.
- 45 10. In combination, a switch throwing and locking mechanism movable between normal and reverse positions and operatively connected with said switch in such manner that said switch will be moved to, and locked in its normal or its reverse position according as said mechanism is moved to its normal or its reverse position, a combined biasing and buffering device including a piston rod movable from a mid stroke position to either end of its stroke in opposition to the bias of a spring and provided with means for retarding movement of the piston rod by said spring, a manually operable lever movable between a normal and a reverse position, means for connecting said manually operable lever with said device in such manner that said device will be moved to a normal or a reverse position according as said lever is moved to a normal or a reverse position, a pivoted bell crank lever, linkage connecting one arm of said bell crank lever with said mechanism and the other arm of said bell crank lever with the piston rod of said device, the arms of said bell crank lever being so proportioned that said mechanism will be biased to its normal or its reverse position by the spring of said device according as said device is moved to its normal or its reverse position, a tie rod connecting the rails at a point between the heel and the point of the switch, and an operating rod pivotally connected at one end with said other arm of said bell crank lever and operatively connected at the other end

- with said tie rod by means of a switch basket and nuts on said operating rod, said nuts being so adjusted that the one nut will be in engagement with said switch basket and the other nut 5 will be out of engagement with said switch basket or vice versa according as said switch occupies its normal or its reverse position but that when said switch is moved from either extreme position to the other the nut which is out of engagement 10 with said switch basket at the beginning of the movement will not move into engagement with said switch basket until after the switch has started its movement.
11. In combination, a switch throwing and locking mechanism movable between normal and reverse positions and operatively connected with said switch in such manner that said switch will be moved to, and locked in its normal or its reverse position according as said mechanism is 15 moved to its normal or its reverse position, a combined biasing and buffering device including a piston rod movable from a mid stroke position to either end of its stroke in opposition to the bias of a spring and provided with means for retarding movement of the piston rod by said spring, a manually operable lever movable between a normal and a reverse position, means for connecting said manually operable lever with said device in such manner that said device will be moved to a 20 normal or a reverse position according as said lever is moved to its normal or its reverse position, a pivoted bell crank lever, linkage connecting one arm of said bell crank lever with said mechanism and the other arm of said bell crank lever with the piston rod of said device, a tie rod connecting the rails at a point approximately midway between the heel and the point of the switch, and an operating rod pivotally connected at one end with said other arm of said bell crank lever and operatively connected at the other end with said tie rod by means of a switch basket and adjusting nuts on said operating rod, the parts being so proportioned that said mechanism will be moved to its normal or its reverse position according as said device is moved to its normal or its reverse position, and that when a train trails the switch the lateral bending of the rails which takes place when the train first enters the switch will act through said tie rod, said operating rod, said bell crank lever and the linkage which connects said one arm of said bell crank lever with said operating mechanism to operate said mechanism to reverse said switch.
13. In combination, a switch throwing and locking mechanism movable between normal and reverse positions and operatively connected with said switch in such manner that said switch will be moved to, and locked in its normal or its reverse position according as said mechanism is 25 moved to its normal or its reverse position, a combined biasing and buffering device including a piston rod extending through said device and movable from a mid stroke position to either end of its stroke in opposition to the bias of a spring, said device being provided with means for retarding movement of the piston rod by said spring, a manually operable lever movable between a normal and a reverse position, means for connecting said manually operable lever with said device in such manner that said device will be moved to a normal or a reverse position according as said lever is moved to its normal or its reverse position, means for connecting one end of said piston rod with said mechanism in such manner that 30 said mechanism will be biased to its normal or its reverse position according as said device is moved to its normal or its reverse position, a pivoted bell crank lever having one arm connected with the other end of said piston rod, a tie rod connecting the rails at a point approximately midway between the heel and the point of the switch, and an operating rod pivotally connected at one end with said other arm of said bell crank lever and operatively connected at the other end with said tie rod by means of a switch basket and adjusting nuts on said operating rod, said nuts being so adjusted that the one nut will be in engagement with said switch basket and the other nut will be out of engagement with said switch basket or vice versa according as said switch occupies its normal or its reverse position but that when said switch is moved from either extreme position to the other the nut which is out of engagement 35 with said switch basket at the beginning of the movement will not move into engagement with said switch basket until after the switch has started its movement.
12. In combination, a switch throwing and locking mechanism movable between normal and reverse positions and operatively connected with said switch in such manner that said switch will be moved to, and locked in its normal or its reverse position according as said mechanism is moved to its normal or its reverse position, a combined biasing and buffering device including a piston rod movable from a mid stroke position to either end of its stroke in opposition to the bias of a spring and provided with means for retarding movement of the piston rod by said spring, a manually operable lever movable between a normal and a reverse position, means for connecting said manually operable lever with said device in such manner that said device will be moved to a normal or a reverse position according as said lever is moved to a normal or a reverse position, a pivoted bell crank lever, linkage connecting one arm of said bell crank lever with said mechanism and the other arm of said bell crank lever with 40
14. In combination, a switch throwing and locking mechanism movable between normal and reverse positions and operatively connected with said switch in such manner that said switch will be moved to, and locked in its normal or its reverse position according as said mechanism is moved to its normal or its reverse position, a combined biasing and buffering device including a piston rod extending through said device and movable from a mid stroke position to either end of its stroke in opposition to the bias of a spring, said device being provided with means for retarding 45

movement of the piston rod by said spring, a manually operable lever movable between a normal and a reverse position, means for connecting said manually operable lever with said device in such manner that said device will be moved to a normal or a reverse position according as said lever is moved to its normal or its reverse position, a pivoted bell crank lever, linkage connecting one end of said piston rod with said mechanism and the other end of said piston rod with one arm of said bell crank lever, a tie rod connecting the rails at a point approximately midway between the heel and the point of the switch, and an operating rod pivotally connected at one end with said other arm of said bell crank lever and operatively connected at the other end with said tie rod

by means of a switch basket and adjusting nuts on said operating rod, the parts being so proportioned that said mechanism will be moved to its normal or its reverse position according as said device is moved to its normal or its reverse position, and that when a train trails the switch the lateral bending of the rails which takes place when the train first enters the switch will act through said tie rod, said operating rod, said bell crank lever, the linkage which connects said bell crank lever with said piston rod, said piston rod, and the linkage which connects said piston rod with said mechanism to operate said mechanism to reverse said switch. 5 10 15
